US00D586385S

(12) **United States Design Patent**
Kim et al.

(10) **Patent No.:** US D586,385 S
(45) **Date of Patent:** ** Feb. 10, 2009

(54) **LASER PRINTER**

(75) Inventors: **Hee-Yul Kim**, Kyunggi-do (KR);
Kwang-Soo Ha, Seoul (KR);
Min-Hyoug Boo, Seoul (KR); **Yun-Gi Hong**, Kyunggi-do (KR)

(73) Assignee: **Samsung Electronics Co., Ltd.**,
Kyunggi-do (KR)

(**) Term: **14 Years**

(21) Appl. No.: **29/294,092**

(22) Filed: **Dec. 21, 2007**

(51) **LOC (9) Cl.** **14-02**

(52) **U.S. Cl.** **D18/55**

(58) **Field of Classification Search** D18/36-39,
D18/50, 54, 54.1, 55; D14/420-425, 462-470;
400/613, 613.1-613.4, 690.1-690.4, 691-694
